AIR CONDITIONING SYSTEM

Montrose K. Drewry, Milwaukee, Wis.

Application September 18, 1933, Serial No. 689,935

15 Claims. (Cl. 257—3)

This invention relates in general to air conditioning systems and particularly to apparatus for conditioning air and circulating it through enclosed spaces.

5 An object of the invention is to provide a simple and efficient air conditioning apparatus for regulating the temperature and humidity conditions of the air in a building.

Another object of the invention is to provide 10 an air conditioning system that is arranged to operate efficiently and with minimum attention.

Another object of the invention is to provide 15 an air conditioning system having means for automatically regulating the rate of combustion of fuel and the rate of circulation of air in accordance with conditions in the space being served with conditioned air.

A further object of the invention is to provide 20 a new method of operating a heat exchange system in which, while the system is used for cooling purposes, the boiler is operated to heat storage water and is at all times prepared to take on a heating load.

According to the present invention, air 25 conditioning apparatus having an air circulating system is provided with an air cleaner, a humidifier and a heat exchanger adapted to heat or cool the air as conditions may require. For heating the air, a boiler provided with an automatic fuel feeding hopper is connected to the heat exchanger, and automatic means are provided for regulating the rate of combustion of fuel in the boiler and the rate of circulation of air in the circulating system in accordance with 30 temperature conditions in the space being heated. Flue gases are drawn through the fuel in the hopper to condition it for feeding by gravity and to improve its qualities for combustion. In warm weather, cold water is circulated through 35 the heat exchanger to cool the air and to condense excess moisture out of it. Coincidentally, the boiler may be utilized for heating service water.

The foregoing and other objects of the invention may be achieved by the air conditioning system described by way of example in the following part of this specification in conjunction with the accompanying drawing, in which the single figure is a view, partly in side elevation 45 and partly in vertical section, of apparatus embodying the invention installed in the basement of a building.

The illustrated air conditioning apparatus comprises, in general, an air circulating system 50 including a conditioning chamber or cabinet 1

of rectangular shape associated with a heating furnace or boiler 2. The air conditioning apparatus is preferably located in the basement of the building to be served and the conditioning chamber 1 may be supported conveniently from 5 the basement ceiling, as shown. Air to be conditioned is drawn from the rooms of the building being served into one or more intake registers 3 and through associated intake pipes or ducts 4 into the conditioning chamber 1. 10

A partition 5, disposed in a vertical medial plane of the chamber 1 and extending from the top downward to near the bottom thereof, divides the chamber into an intake compartment 6, to the top of which the intake pipes 4 are 15 connected, and a discharge compartment 7. The partition 5 constrains the flow of the incoming air and directs it downward through a filter 8 arranged horizontally in the intake compartment 6 in position to remove dust and other 20 foreign particles from the air. From the filter, the air flows downward to the bottom of the compartment 6 and thence horizontally through a connecting passageway beneath the lower end of the partition 5 into the compartment 7. 25

At the bottom of the compartment 7, there is arranged a humidifying tank or pan 9 that presents a surface of warm water to the inflowing filtered air from which the air absorbs 30 a predetermined amount of moisture.

Above the humidifier 9, there is arranged a heat exchanging radiator 10 that functions to heat or cool the air, according to the requirements of weather conditions, as it flows upward in the compartment 7. From the top of the compartment 7, the air flows into outlet pipes 11 through which it is delivered to one or more discharge registers 12 in the rooms of the building being served, the air circulating system functioning, in general, in much the same manner 35 as the circulating system of the usual warm air furnace.

The heat exchanger 10 is of the fin-and-tube type, having an inlet manifold or header 13 which is connected by an inlet pipe 14 to the 45 upper part of the boiler 2 and from which a bank of finned tubes 15 extends horizontally across the compartment 7 to a return header 16. From the return header 16, a second bank of finned tubes 17 extends across the compartment 50 beneath the tubes 15 to a discharge header 18 which is connected by a return pipe 19 to the lower part of the boiler 2. The tubes 15 and 17 are so spaced and positioned that the air, in flowing upward through the heat exchanger, 55

first passes between the tubes 17 of the lower bank and then passes between the tubes 15 of the upper bank.

As shown in the drawing, the heat exchanger 10 is arranged substantially at the level of the top of the boiler 2 to facilitate the circulation of hot water from the boiler through the water circulating system. In cold weather, when the system is being used for heating the building, hot water from the top of the boiler 2 flows horizontally through the inlet pipe 14 into and through the upper tubes 15 and then back through the lower tubes 17 of the heat exchanger 10 in series relation, giving up a portion of its heat to the air in the compartment 7. The water then flows from the heat exchanger into the vertically arranged return pipe 19 and thence back to the bottom of the boiler.

As the column of relatively cool water in the vertical return pipe 19 is heavier than the corresponding column of hot water in the boiler, it descends by gravity, causing circulation by natural convection or thermo-syphon action through the heat exchanger. Because the heat exchanger 25 is positioned substantially level with the top of the boiler, the column of cool water in the return pipe 19 is of sufficient height to cause effective thermo-syphon action in the system.

The air in the circulating system likewise is caused to circulate by thermo-syphon action, the heated air in the compartment 7 rising into the outlet pipes 11 and being replaced by cool air from the compartment 6. To effect circulation of the air by thermo-syphon action it is desirable 35 that the heat exchanger be placed as low as possible in the air circulating system in order that the column of heated air may be of sufficient height to establish a difference in weight between it and the corresponding column of cold air great 40 enough to provide pressure for effective circulation. By positioning the heat exchanger at the level of the boiler top, the conditions necessary for thermo-syphon circulation of both the water and the air are met in manner to effect equally 45 satisfactory circulation of each.

The boiler 2 is provided at its top with an expansion tank or chamber 20 that serves as a storage reservoir for water which may be forced out of the boiler when the water therein is expanded by heat. The tank 20, being open to the atmosphere, also permits the escape of air or steam that might otherwise interfere with the circulation of the water through the system, should the pipe 14 become air-bound or steam-bound by reason of becoming filled with either fluid.

An adequate supply of water is automatically maintained in the boiler at all times by means of an inlet valve 21 that controls the inflow of water from a supply pipe 22 to make up for water lost by evaporation or otherwise. The valve 21 is actuated automatically by a float 23 resting on the surface of the water in the expansion tank. The float 23 covers substantially all of the surface of the water in the tank and greatly reduces the absorption of air by the water when it cools below its boiling temperature, thereby avoiding corrosion of the interior of the water circulating system apparatus by air dissolved in the water.

Fuel for combustion in the firebox of the boiler 2 is fed into the firebox automatically by gravity from an air-tight fuel hopper 24 mounted on one side of the boiler. The hopper 24 may be filled periodically with solid fuel such as coal or coke 75 through an opening 25 in its top which is nor-

mally closed by a close-fitting removable cover 26. The flue gases resulting from combustion of the fuel are conducted from the firebox by a smoke-pipe 27 that discharges into a chimney 28.

A relatively small pipe 29 is connected between the smoke-pipe 27 and the upper part of the fuel hopper 24 for conducting flue gases from the smoke-pipe into the top of the hopper to be drawn downward through the fuel by the natural draft of the firebox to condition the fuel for feeding and burning. The flue gases passing through the hopper, together with heat conducted from the boiler to the hopper, act upon the fuel therein in such manner that water vapor and certain gases are driven off and the fuel is otherwise so modified as to prevent burning or clogging thereof in the hopper or caking upon flowing from the hopper into the firebox. The conditioned fuel flows into the firebox by gravity continually and automatically at the rate at which it is required to replace the fuel consumed, thus maintaining a uniform bed of burning fuel on the firebox grate at all times.

An opening 30 is provided in the side of the firebox above the level of the fuel bed therein for introducing auxiliary air into the combustion chamber. To control the amount of auxiliary air introduced, the opening is provided with an adjustable cover 31. The opening 30 may be utilized for starting the fire when the hopper contains a supply of fuel, as kindling materials may be inserted through it into the firebox and ignited. A further function of the opening 30 is to permit observation of the condition of the fire.

The rate of combustion of fuel in the firebox and the rate of heating resulting therefrom is regulated by a thermostat 32 so located as to be responsive to the temperature of the air in the rooms being heated and arranged to be regulated to maintain the air in the rooms at a predetermined desired temperature. The thermostat 32 is connected to a thermostat motor 33 in such manner as to energize it in response to changes in the room temperature. The thermostat motor 33 is connected, by a continuous chain 34 carried by pulleys 35, to operate a draft door 36 arranged to control the admission of air into the firebox beneath the bed of fuel therein, and to operate a check door 37 arranged to control the admission of air into the base of the chimney 28 for checking the fire.

When the temperature of the air in the rooms being heated falls below the predetermined desired temperature for which the thermostat is set, the thermostat and its associated motor function to close the chimney check door 37 and to open the draft door 36, thereby increasing the draft through the firebox and increasing the rate of combustion of fuel to furnish additional heat to the boiler water.

The boiler is provided with a water temperature regulator 38 that includes a thermo-expansion element 39 disposed in contact with the water in the boiler and connected by a link 40 to a pivoted lever arm 41 on which is slidably mounted an adjustable counterpoise weight 42. As the temperature of the boiler water increases in response to the action of the thermostat 32, the thermal expansion element 39 expands and pivots the lever arm 41, lifting the weight 42. When the water temperature reaches a predetermined value, the lever arm 41 is pivoted to such position that an electrical switch 43, pref-

erably of the mercury type, mounted on the lever arm 41 closes and completes an electric circuit that leads from a power line 44 through conductors 45 to a motor 46 connected to a fan 47 disposed in the lower part of the intake compartment 6. The fan is so directed as to increase the circulation of air through the system by forcing air from the intake compartment 6 into the discharge compartment 7 and upward through the heat exchanger 10. The increased circulation of air through the heat exchanger results in conveying additional heat from the hot water circulating through it and consequently tends to reduce the temperature of the water in the boiler. The additional heat transferred from the boiler water is conveyed by the air to the rooms being heated and raises the room temperature in response to the functioning of the thermostat 32.

When the predetermined normal temperature in the rooms is restored, the thermostat 32 actuates the thermostat motor 33 to cause it to close the draft door 36 and to open the check door 37, thereby decreasing the rate of combustion of fuel in the firebox and reducing the amount of heat supplied to the boiler.

When the temperature of the water in the boiler becomes reduced below a predetermined value, as a result of the action of the fan and of the reduced rate of combustion of fuel effected by the thermostat, the thermal expansion element 39 contracts and permits the weight 42 to pivot the lever arm 41 in such manner as to open the switch 43 and stop the fan motor 46, thereby reducing the amount of heat supplied to the rooms and preventing the room temperature from exceeding the predetermined maximum.

If the predetermined normal temperature in the rooms is not restored within a short time, the temperature of the boiler water will continue to increase while the fan 47 is operating in spite of the cooling effect of the fan, and the water temperature regulator 38 will function, through a connection with the draft and check doors, to reduce the rate of fuel combustion and prevent overheating of the boiler water. This action of the water temperature regulator will occur regardless of the fact that the thermostat motor 33 may be tending, at the time, to increase the rate of fuel combustion.

To enable this result to be accomplished, the continuous chain 34 of the draft regulating mechanism is connected to the draft door and to the check door by means of pulleys 48, one of which is mounted on each door, the pulleys being arranged to rotatably receive the chain. The run of the chain at the sides of the pulleys 48 opposite from the run thereof that is connected to the thermostat motor 33, is attached to the end of the lever arm 41, as shown. When the temperature of the boiler water exceeds a predetermined maximum, the lever arm 41 of the temperature regulator 38 is moved to the position shown in the drawing and in so doing actuates the chain 34 to close the draft door 36 and to open the check door 37 independently of the action of the thermostat motor 33. As the thermal expansion element 39 which operates the arm 41 expands or contracts in accordance with temperature changes of the water in the boiler, its action causes the temperature regulator 38 to actuate the draft door and the check door in modulating manner to maintain the temperature of the boiler water substantially constant. This arrangement prevents overheating of the boiler water and prevents the formation of excess

steam which would otherwise interfere with the circulation of the water through the heat exchanger 10 by steam-binding the pipe 14.

The water temperature which the regulator 38 will tend to maintain in the boiler and the temperature at which the fan motor will be started or stopped, may be regulated by adjusting the position of the weight 42 along the lever arm 41. An incidental effect of this adjustment is to regulate the amount of time during which the fan 47 will operate under given conditions. For example, if the weight 42 is set to maintain relatively high water temperature the fan will not operate as much of the time as it will in delivering an equal amount of heat when the weight 42 is set to maintain relatively low water temperature.

The smoke-pipe 27 is made air-tight in order that the flue gases it conducts to the chimney 28 may surrender the maximum amount of heat 20 to the basement air and thus decrease fuel costs. Ordinarily, in the usual furnace installation a check door is located in the smoke-pipe near the boiler, but the air it admits at this location so cools the flue gases passing through the smoke-pipe that most of the flue gas heat is wasted by escaping up the chimney. Also, deterioration of the smoke-pipe is ordinarily more rapid when air is admitted to it than is the case with the air-tight design illustrated in the drawing. 30

For heating service water, an indirect water heater 49 is connected in a minor circulating system paralleling the main circulating system through the heat exchanger. This minor circulating system includes a pipe 50 leading from the pipe 14 at the top of the boiler to the heater 49, and a pipe 51 leading from the heater to the return pipe 19 near the bottom of the boiler. The service water circulates from the bottom of a hot water storage tank 52, through a pipe 53 upward 40 into and through a heating coil in the heater 49 and thence through a pipe 54 into the top of the storage tank. Water is supplied to the bottom of the hot water storage tank 52 through a pipe 55 that is connected to the supply pipe 22, and hot 45 water is delivered from the top of the tank through a pipe 56 that leads to the various positions throughout the building at which the hot water is utilized.

Circulation of water from the boiler through the heater 49 occurs because of the fact that the temperature of the water is lowered in imparting heat to the service water in the heating coil. Consequently, the column of water in the vertical return pipe 51 is cooler and denser than a corresponding column of water in the boiler, and the cool water column descends through the pipe 51 by gravity, causing circulation by natural convection. 55

The circulating water in the pipe 51 is utilized 60 to provide heat for evaporating the water in the humidifying tank 9. As shown, the humidifier is provided with a submerged heating coil 56 into which water may flow from the pipe 51 through a pipe 57 and from which it flows through a pipe 58 65 to the return pipe 19. The flow of water through the heating coil 56 may be regulated by a valve 59 in the pipe 57 and a valve 60 arranged to close the portion of the pipe 51 between the pipe 57 and the pipe 19. By manipulating these valves, the temperature of the water in the humidifier may be controlled, thus regulating the rate of evaporation of the water and the humidification of the air circulating through the conditioning chamber. As a further means of controlling the action of the 75

humidifier, the amount of water surface exposed to the air may be regulated by covering a portion of the tank 9.

The level of the water in the humidifying tank 9 is maintained substantially constant by a float-operated valve 61 which automatically admits water from a pipe 62 that is connected to the supply pipe 22 to replenish water evaporated in humidifying the air. To prevent corrosion of the humidifier or the formation of scale therein, chemicals of the nature ordinarily utilized in steam boilers for such purposes may be added to the water.

In front of the fan 47 and over the humidifying tank 9, there is arranged a series of directing vanes 63 that turn the circulating air uniformly upward into the heat exchanger 10 with minimum loss of energy.

Auxiliary air may be introduced into the circulating system through an auxiliary air intake pipe 64 extending from the intake compartment 6 out of doors for admitting fresh outside air and having a damper 65 for controlling the volume of air admitted. A second auxiliary air intake pipe 66 opening into the basement is connected to the compartment 6 and is likewise provided with a damper 67 for controlling the volume of air admitted from the basement into the system.

During warm weather the air conditioning system is utilized for cooling and drying the air in the building. To adjust the system for this mode of operation, a valve 68 in the pipe 14 and a valve 69 in the pipe 19 are closed to isolate the heat exchanger 10 from the boiler, leaving the minor circulating system through the service water heater 49 connected to the boiler. Cold water from the supply pipe 22 is then admitted to the heat exchanger through a pipe 70 having a control valve 71 which leads into the pipe 14. From the pipe 14 the water flows through the upper bank of tubes 15 of the heat exchanger to the header 16 and then back through the lower bank of tubes 17 into the header 18 and the return pipe 19 from which it escapes through a discharge valve 72 into a discharge pipe 73. Ordinarily, the water discharged through the pipe 73 is put to some useful purpose, as for supplying a fountain and pool or for watering the lawn or garden, such use being suggested by a faucet 74 which is provided at the end of pipe 73 that extends out of doors for attaching a hose. Refrigerated water or other cooling fluid may be circulated through the heat exchanger instead of water from the usual city supply.

For circulating the air through the circulating system while the cold water is passing through the heat exchanger, the fan motor 46 is operated to drive the fan 47 continuously. To provide for selectively operating the fan motor 46, a manually operated push-button switch 75 is arranged to connect the conductors 45 which lead to the motor directly to the power line 44. Another push-button switch 76 is arranged in the circuit of the mercury switch 43 on the lever arm 41 and may be opened to render the mercury switch inoperative while the system is being used for cooling.

The fan 47 forces the air upward first through the spaces between the lower tubes 17 and then through the spaces between the upper tubes 15 of the heat exchanger. In this manner the air first comes in contact with and is cooled by the tubes containing water that has been warmed somewhat, and then the partly cooled air passes over the tubes containing the cold water. This is in accordance with the counterflow principle of heat

transfer wherein the warmest air comes in contact with the warmest tubes and the coolest air passes over the coldest tubes, the arrangement which is generally recognized as the most efficient for the transfer of heat between fluids.

During the period in which the apparatus is being used to cool the air, the supply of water to the humidifier 9 is interrupted by closing a valve 77 in the pipe 62, and the water is drained from the tank by opening a valve 78 in a drain-pipe 79. When the warm air from the rooms comes in contact with the cold tubes of the heat exchanger, the excess water vapor in the air condenses upon the surface of the tubes, thus reducing the humidity of the air. The moisture which collects on the tubes drips into the humidifier tank 9 and is drained away through the open drain-pipe 79.

While the air circulating system is being utilized to cool the air in the building, the boiler 2 may be used for heating the service water. To provide automatic regulation of the service water temperature, the thermostat 32 is rendered inoperative by adjusting it to a high temperature setting, in which position it will tend to hold the draft door 36 open continuously and to hold the chimney check door 37 closed continuously. The adjustable weight 42 on the water temperature regulator 38 is then so positioned that the regulator 38 will operate to close the draft door 36 and open the check door 37 in opposition to the tendency of the thermostat when the desired service water temperature is attained. The regulator thus adjusted will maintain a low fire in the firebox to heat the service water to a predetermined temperature without further attention to the apparatus other than refilling the fuel hopper 24, which ordinarily is necessary only at weekly intervals. Should changing weather conditions, such as occur in the spring or in the fall, make it desirable to change the mode of operation of the apparatus from cooling to heating because of a sudden drop in temperature, it is merely necessary to shut off the flow of cold water through the heat exchanger and reconnect it to the boiler by opening the valves 68 and 69. The hot water always available in the boiler provides instant heating effect and the continuously burning fire can at once be placed under the control of the thermostat 32 to bring the air in the rooms to the desired temperature.

Although a specific air conditioning system has been described in detail herein for the purpose of clearly disclosing a practical embodiment of the invention, it is to be understood that the particular structure set forth is susceptible of modification without departing from the spirit and scope of the invention as defined by the subjoined claims.

It is claimed and desired to secure by Letters Patent:

1. An air conditioning system for serving a plurality of spaces comprising a conditioning chamber, a plurality of air intake pipes connected to said chamber for drawing air to be conditioned from said plurality of spaces being served, other air inlet pipes connected to said chamber for admitting air from other sources, means for controlling the amount of air admitted through said latter inlet pipes, an air filter arranged in said chamber in position to filter the air drawn through said inlet pipes, a humidifying apparatus arranged in said chamber to humidify the filtered air, regulatable means arranged to heat said humidifying apparatus for regulating

the humidifying action thereof, a heat exchanger arranged in said chamber to heat said filtered and humidified air and to cause it to circulate through said chamber by thermo-syphon action, a plurality of delivery pipes connected to said chamber for receiving and distributing the conditioned air to said plurality of spaces, a fan arranged in said chamber for assisting the circulation of air therethrough, and means operative in response to conditions in said spaces being air conditioned for controlling the operation of said fan.

2. An air conditioning system for alternate heating and cooling of an enclosed space, comprising a boiler for heating water, a heat exchanger, means connecting said heat exchanger to said boiler in such manner as to permit flow of hot water from said boiler through said heat exchanger by thermo-syphon action, an air conditioning chamber enclosing said heat exchanger, means for circulating air being conditioned through said chamber in contact with said heat exchanger and into the space being served to heat said space, means for automatically regulating said boiler in response to conditions in the space being served with conditioned air, a tank for storing warm service water, a service water heater connected to be heated by said boiler and arranged to supply warm water to said service water tank, means for closing said heat exchanger connecting means to isolate said heat exchanger from said boiler, means for circulating cooling fluid through said heat exchanger when isolated from said boiler to cool the space being served, and means for automatically regulating the fire in said boiler in response to the temperature of the water therein in manner tending to maintain the water temperature substantially constant to heat service water automatically for storage in said service water tank while said heat exchanger is being utilized for cooling the conditioned air thereby keeping the fire active and instantly available for heating the space being served upon opening the connecting means between said boiler and said heat exchanger.

45 3. A space heating system for automatic heating by the combustion of solid fuel, comprising a boiler for heating water and having a firebox for burning solid fuel provided with draft control dampers, a heat exchanging radiator connected to the top and the bottom of said boiler and disposed substantially at the level of the top of said boiler in position to facilitate thermo-syphon circulation of water therethrough, an air conditioning chamber enclosing said heat exchanger and arranged to facilitate thermo-syphon circulation of air through said radiator and into the space being heated, a fan disposed within said chamber and operative to accelerate the circulation of air through said heat exchanging radiator, means responsive to the temperature of the water in said boiler connected to cause said fan to operate when said water attains a predetermined temperature to accelerate the transfer of heat to the space being heated and for so regulating the draft control dampers of said firebox as to tend to maintain the boiler water temperature uniform, means responsive to the temperature of the air in the space being heated and connected to superimpose its action upon that of the water temperature regulator to so regulate the draft control dampers of said firebox as to tend to maintain the temperature of said air constant, a fuel hopper disposed to automatically feed fuel by gravity into said firebox continuously to replace the fuel consumed there-

in and to maintain a uniform fuel bed, and means for conducting flue gases from said firebox through the fuel in said hopper to condition it for uniform automatic feeding into said firebox whereby completely automatic space heating by 5 the combustion of solid fuel is effected.

4. A space heating system, comprising a boiler for heating water and having a firebox provided with draft control dampers, a heat exchanging radiator connected to the top and to the bottom of said boiler and disposed horizontally at the level of the top of said boiler in position to facilitate thermo-syphon circulation of water therethrough, an air conditioning chamber having a vertically disposed compartment enclosing 10 said heat exchanging radiator and arranged to direct air upward therethrough, air pipes connecting said chamber to the space being heated and arranged to facilitate thermo-syphon circulation of air through said radiator and into 15 said space being heated, a filter disposed in said chamber in position to filter the incoming air, a humidifying tank disposed in said chamber beneath said radiator to humidify the filtered air, a fan disposed in said chamber and operative to 20 accelerate the circulation of air through said heat exchanging radiator, means responsive to the temperature of the water in said boiler connected to cause said fan to operate when said water attains a predetermined temperature and 25 connected to so regulate the draft control dampers of said firebox as to tend to maintain the boiler water temperature uniform, and means responsive to the temperature of the air in the space being heated and connected to superimpose 30 its action upon that of the water temperature regulator to so regulate the draft control dampers of said firebox as to tend to maintain uniform temperature in said heated space.

5. An air conditioning system for conditioning 40 air in a plurality of spaces, comprising a cabinet of substantially rectangular shape provided with a medially disposed dividing wall extending from the top thereof downwardly dividing the cabinet into an intake compartment and a 45 discharge compartment with a connecting passageway along the bottom thereof, a plurality of inlet pipes connected to the top of said intake compartment for admitting air to be conditioned, a filter arranged in said intake compartment beneath said inlet pipes to filter said air, a fan disposed in said intake compartment beneath said filter and directed towards the connecting passageway for circulating air through said cabinet, a humidifying pan disposed on the bottom of the 50 discharge compartment in front of said fan in position to receive an air blast therefrom, means in said humidifying pan for heating water therein to humidify the air blown over the water by said fan, a heat exchanger disposed directly 55 above said humidifying pan in said discharge compartment for heating said air, and a plurality of outlet pipes connected to the top of said discharge compartment for delivering the conditioned air to a plurality of spaces being served. 60

6. An air conditioning system for conditioning 65 air in a plurality of spaces in a building, comprising a cabinet divided by a medial dividing wall into an intake compartment and a discharge compartment connected by a horizontal passage 70 along the bottom thereof, a plurality of air inlet pipes connected to the top of said intake compartment and communicating with the plurality of spaces being conditioned for drawing air therefrom, an auxiliary air inlet pipe connected to the 75

- top of said intake compartment and communicating with the exterior of the building for admitting outside air into the system, means for controlling said auxiliary air inlet to regulate the amount of outside air admitted into the system, an air filter arranged in said intake compartment beneath said inlet pipes in position to filter air drawn into said intake compartment, a fan disposed in said intake compartment beneath said filter and directed toward the horizontal passageway into the discharge compartment, a humidifying pan disposed in the bottom of said discharge compartment in position to receive a blast of air from said fan for humidifying said air, a heat exchanger disposed in said discharge compartment above said humidifying pan for heating said air, and a plurality of outlet pipes connected to the top of said discharge compartment and communicating with the plurality of spaces being conditioned for delivering conditioned air to said spaces.
7. An air conditioning apparatus adapted for installation in the basement of a building for conditioning the air in other parts of the building, comprising an air conditioning cabinet having a medial dividing wall separating it into an intake compartment and a discharge compartment connected by a horizontal passage along the bottom thereof, an air inlet pipe connected to the top of said intake compartment and communicating with the part of the building being served to withdraw air therefrom for conditioning said air, an auxiliary air inlet pipe connected to the top of said intake compartment and communicating with the exterior of the building for admitting outside air into said cabinet, means for controlling the amount of outside air admitted through said auxiliary inlet pipe, an auxiliary air inlet opening in the top of said intake compartment for admitting basement air into said cabinet, means for controlling the amount of basement air admitted through said auxiliary opening, an air filter arranged in said intake compartment below said air inlets in position to filter the incoming air, a fan disposed beneath said filter to circulate air from said intake compartment into said discharge compartment, a humidifying pan disposed in the bottom of said discharge compartment to humidify said circulating air, a heat exchanger disposed in said discharge compartment above said humidifying pan to heat said air, and an air outlet pipe connected to the top of said discharge compartment and communicating with the parts of the building being served to deliver conditioned air thereto.
8. A heating system, comprising a boiler for heating water, a heat exchanger cabinet associated with said boiler, a radiator disposed in said heat exchanger cabinet and connected to said boiler for transferring heat from said boiler to air in said heat exchanger, a humidifying pan disposed in the bottom of said heat exchanger cabinet for evaporating water to humidify the air being heated, a heating coil in said humidifying pan for heating water therein, a circulating system connecting said humidifying pan heating coil with said boiler, and a service water heating coil connected in said circulating system near the top of said boiler and arranged to heat service water by transfer of heat from said boiler water, whereby circulation of boiler water through said humidifying pan heating coil is effected by reason of the drop in temperature of said boiler water in said service water heating coil resulting in thermo-syphon action in said circulating system.

9. A space heating system comprising a boiler for heating water by the combustion of fuel and having draft control means, a lever pivotally mounted on said boiler and connected to operate said draft control means, a thermo-expansive temperature responsive means associated with said boiler and connected to rock said lever in accordance with changes in temperature of said boiler water to actuate said draft control in manner tending to maintain the temperature of said boiler water substantially constant, means responsive to the temperature of the space being heated and arranged to change the connection between said lever and said draft control means upon the temperature of said space falling below a predetermined minimum value to cause said temperature responsive means to tend to maintain said boiler water at a higher temperature than is maintained when said space temperature is above said minimum value, means controlled by said pivoted lever for increasing the rate of delivery of heat to the space being heated upon said boiler water exceeding a predetermined temperature, and a weight slidably mounted on said pivoted lever for adjusting the relation of said lever to said thermo-expansive means to regulate the temperature of said boiler water and the operation of said heat delivery increasing means.
10. In a space heating system for closely regulated heating by the combustion of solid fuel, the combination with a boiler for heating water provided with a firebox for the combustion of solid fuel, of means for feeding solid fuel into said firebox uniformly by action of gravity, means for regulating the draft of said firebox to control the rate of combustion of said fuel therein, means responsive to the temperature of water in said boiler and adapted to exert force for moving said draft regulating means in modulating manner in accordance with changes in the water temperature and proportionately thereto, means for adjusting said water temperature responsive means to change its range of movement relative to the temperature of said boiler water, adjustable operating means connecting said water temperature responsive means to said draft regulating means to enable modulating operation of said draft regulating means in accordance with changes of boiler water temperature to control the rate of combustion in said firebox in manner tending to maintain said boiler water at a uniform temperature determined by the adjustment of said water temperature responsive means, and means responsive to the temperature of the air in the space being heated connected to said adjustable operating means in manner to change the relation of said water temperature responsive means to said draft regulating means to effect greater opening of said draft regulating means when the air temperature falls below a predetermined minimum tending to maintain said boiler water at a higher temperature than obtains when said air temperature is above said predetermined minimum, and means controlled by said water temperature responsive means for increasing the rate of heat movement to said space being heated upon the temperature of said boiler water exceeding a predetermined maximum.

11. A space heating system comprising a boiler for heating water by the combustion of fuel, a heat exchange radiator associated with said boiler, a water circulating system connecting said radiator to said boiler in manner to provide thermo-syphon circulation of boiler water through said radiator, an air circulating system enclosing

said radiator and disposed in manner to provide thermo-syphon circulation of air through said radiator and into the space being heated, combustion control mechanism associated with said boiler for regulating the rate of fuel combustion therein, means responsive to the temperature of water in said boiler for continuously regulating said combustion control mechanism in modulating manner tending to maintain the temperature 10 of said boiler water substantially constant, means responsive to the temperature of the air in the space being heated for changing the relation of said water temperature responsive means and said combustion control mechanism to cause said water temperature responsive means to actuate said combustion control mechanism in manner tending to maintain said boiler water at a higher temperature upon the space temperature falling below a predetermined minimum than is maintained 20 when the space temperature is above said predetermined minimum to increase the rate of heating by said boiler, a fan disposed in said air circulating system in position to augment the circulation of air therethrough, and means actuated 25 by said water temperature responsive means controlling the operation of said fan to cause it to operate when the temperature of said boiler water exceeds a predetermined maximum to increase the circulation of air through said radiator there- 30 by increasing the rate of delivery of heat from said radiator to the space being heated and consequently increasing the rate of thermo-syphon circulation of water through said radiator to increase the rate at which heat is conveyed from 35 said boiler to said radiator.

12. An air conditioning system for selectively heating or cooling an enclosed space, comprising a boiler for heating water, a heat exchanger arranged to serve said enclosed space, means connecting said heat exchanger to said boiler in manner to permit circulation of hot water from said boiler through said heat exchanger to heat said space, means to close off said connecting means to isolate said boiler from said heat ex- 40 changer, a service water heating system associated with said boiler including a tank for storing heated service water and a water heater disposed to be heated by said boiler and connected to supply hot water to said storage tank, means ar- 45 ranged to circulate cooling fluid through said heat exchanger while it is isolated from said boiler by said closing off means to cool said space being served, and means for automatically regulating said boiler in response to the temperature of the 50 water therein in manner tending to maintain the water temperature substantially constant to provide modulated regulation thereof while said boiler is functioning to heat said space and to pro- 55 vide for automatically heating service water to a predetermined temperature for storage in said tank while said boiler is isolated from said heat exchanger whereby said boiler is maintained in 60

active operation while isolated from said heat ex- 5 changer and is therefore instantly available for quickly heating the space being served upon opening said closing off means to admit hot water from said boiler into said heat exchanger.

13. An air conditioning system for selectively heating or cooling an enclosed space, comprising a boiler for heating water, a heat exchanger arranged to serve said enclosed space, means connecting said heat exchanger to said boiler in manner to permit circulation of hot water from said boiler by natural convection through said heat exchanger to heat said space, manually operable means to close off said connecting means to isolate said boiler from said heat exchanger, a service water heating system associated with said boiler including a tank for storing heated service water and a water heater disposed to be heated by said boiler and connected to supply hot water to said storage tank, means arranged to circulate cooling 10 fluid through said heat exchanger while it is isolated from said boiler by said closing off means to cool said space being served, and means for automatically regulating said boiler in response to the 15 temperature of the water therein in manner tending to maintain the water temperature substantially constant to provide modulated regulation thereof while said boiler is functioning to heat said space and to provide for automatically 20 heating service water to a predetermined temperature for storage in said tank while said boiler is isolated from said heat exchanger whereby said boiler is maintained in active operation while isolated from said heat exchanger and is therefore 25 instantly available for quickly heating the space 30 being served upon opening said closing off means to admit hot water from said boiler into said heat 35 exchanger.

14. The method of operating a heat exchange system which comprises circulating a heat conducting medium through a boiler in circuit with a heat exchanger and a storage water heater during cold weather, and isolating the heat exchanger from the boiler and storage water heater in warm weather and passing a cooling fluid 40 through the heat exchanger, and maintaining the boiler in operation to provide heat for the storage water heater and to provide reserve heat for the 45 heat exchanger.

15. In combination, a boiler, a hot water storage tank, a cabinet, a heat exchanger in said cabinet, a fan for forcing air through said cabinet, a source of cold water supply, adjustable means connecting said heat exchanger with said source, said boiler and said storage tank whereby air may 50 be heated or cooled in said cabinet while the boiler remains in operation, and thermostatic means for automatically controlling said boiler for air heating requirements, said means also controlling the boiler for storage water heating while the cabi- 55 net is serving as a cooling means.
